(57) **CLAIM**

The ornamental design for a casement window operator handle and cover, as shown and described.

DESCRIPTION

FIG. 1. is a right isometric view of the casement window operator handle and cover;

FIG. 2. is a left isometric view of the casement window operator handle and cover;

FIG. 3. is a right elevation view of the casement window operator handle and cover;

FIG. 4. is a left elevation view of the casement window operator handle and cover;

FIG. 5. is a front elevation view of the casement window operator handle and cover;

FIG. 6. is a top plan view of the casement window operator handle and cover;

FIG. 7. is a rear elevation view of the casement window operator handle and cover; and,

FIG. 8. is a bottom plan view of the casement window operator handle and cover.

The broken lines in the drawings depict portions of the casement window operator handle and cover that form no part of the claimed design.

1 Claim, 5 Drawing Sheets
